(57) **CLAIM**

The ornamental design for a mobile service robot, as shown and described.

DESCRIPTION

FIG. 1 a perspective view of the mobile service robot according to the present invention.

FIG. 2 displays the perspective view of the mobile service robot in a state where the front part is opened.

FIG. 3 is a front view of the mobile service robot of FIG. 1. FIG. 4 displays the front view of the mobile service robot in a state where the front part is opened.

FIG. 5 is a rear view of the mobile service robot of FIG. 1. FIG. 6 displays the rear view of the mobile service robot in a state where the front part is opened.

FIG. 7 is a left side view of the mobile service robot of FIG. 1.

FIG. 8 displays the left side view of the mobile service robot in a state where the front part is opened.

FIG. 9 is a right side view of the mobile service robot of FIG. 1.

FIG. 10 displays the right side view of the mobile service robot in a state where the front part is opened.

FIG. 11 is a top view of the mobile service robot of FIG. 1; and,

FIG. 12 displays the top view of the mobile service robot in a state where the front part is opened.

1 Claim, 12 Drawing Sheets
